(57) **CLAIM**

The ornamental design for a kinetic intervention device, as shown and described.

DESCRIPTION

FIG. 1 is a front perspective view of a kinetic intervention device in accordance with an embodiment of the present design;

FIG. 2 is a front elevation view of the kinetic intervention device of FIG. 1;

FIG. 3 is a rear elevation view front elevation view of the kinetic intervention device of FIGS. 1 and 2;

FIG. 4 is a top plan view of the kinetic intervention device of FIGS. 1–3;

FIG. 5 is a bottom plan view of the kinetic intervention device of FIGS. 1–4;

FIG. 6 is a right side elevational view of the kinetic intervention device of FIGS. 1–5;

FIG. 7 is a left side elevational view of the kinetic intervention device of FIGS. 1–6; and,

FIG. 8 is a plan view of the kinetic intervention device of FIGS. 1–7 shown in a twisted configuration.

In FIGS. 1–8, the features of the kinetic intervention device shown in broken lines represent a strap for environmental purposes only and do not constitute a part of the claimed design.
